Primary Examiner—Prabhakar Deshmukh(57) **CLAIM**

The ornamental design for game target-poker shoot, as shown and described.

DESCRIPTION

FIG. 1 is a front elevational view of a game target-poker shoot showing my new design.

All other views, which are not shown in the drawing, have been disclaimed.

The right and left side elevational views, and top and bottom plan views are each essentially flat and do not constitute a part of the claimed design. The rear elevational view is not visible during normal use while target shooting, and does not constitute a part of the claimed design.
